(57) **CLAIM**

The ornamental design of the slatwall extrusion, as shown and described.

DESCRIPTION

FIG. 1 is a perspective view of the new slatwall extrusion design having two panels with a hanger lip at each of their lower ends, and with its connecting ends shown in broken lines;

FIG. 2 is a front view of the slatwall extrusion;

FIG. 3 is a rear view of the slatwall extrusion;

FIG. 4 is a top end view of the slatwall extrusion;

FIG. 5 is a bottom end view of the slatwall extrusion;

FIG. 6 is a side view of the slatwall extrusion showing it mounted to a wall and supporting a hanger bracket, which are both shown in broken lines;

FIG. 7 is a perspective view of a second embodiment of the new slatwall extrusion design having two panels with an offset hanger lip and cross web at each of their lower ends, and with its cross web and connecting ends shown in broken lines;

FIG. 8 is a side view of the second embodiment of the slatwall extrusion;

FIG. 9 is a perspective view of a third embodiment of the new slatwall extrusion design having two panels with a hanger lip and offset cross web at each of their lower ends, and with the cross web and its connecting ends shown in broken lines;

FIG. 10 is a side view of the third embodiment of the slatwall extrusion;

FIG. 11 is a perspective view of a fourth embodiment of the new slatwall extrusion design having three panel with a hanger lip at its lower end, and with its connecting ends shown in broken lines;

FIG. 12 is a perspective view of a fifth embodiment of the new slatwall extrusion design having three panels with an offset hanger lip and cross web at each of their lower ends, and with its cross web and connecting ends shown in broken lines;

FIG. 13 is a perspective view of a sixth embodiment of the new slatwall extrusion design having three panels with a hanger lip and offset cross web at each of their lower ends, and with the cross web and its connecting ends shown in broken lines;

FIG. 14 is a side view of the fourth embodiment of the slatwall extrusion;

FIG. 15 is a side view of the fifth embodiment of the slatwall extrusion;

FIG. 16 is a side view of the sixth embodiment of the slatwall extrusion;

FIG. 17 is a perspective view of a seventh embodiment of the new slatwall extrusion design having four panel with a hanger lip at its lower end, and with its connecting ends shown in broken lines;

FIG. 18 is a perspective view of a eighth embodiment of the new slatwall extrusion design having four panels with an offset hanger lip and cross web at each of their lower ends, and with the cross web and its connecting ends shown in broken lines;

FIG. 19 is a perspective view of a ninth embodiment of the new slatwall extrusion design having four panels with a hanger lip and offset cross web at each of their lower ends, and with the cross web and its connecting ends shown in broken lines;

FIG. 20 is a side view of the seventh embodiment of the slatwall extrusion;

FIG. 21 is a side view of the eighth embodiment of the slatwall extrusion; and,

FIG. 22 is a side view of the ninth embodiment of the slatwall extrusion.

The side views opposite those in FIGS. 6, 8, 10, 14–16 and 20–22 are mirror images. The broken lines showing the connecting ends, fastener holes, cross web, wall and hanger are for illustrative purposes only and form no part of the claimed design. The remaining broken lines in the drawings are to disclose the indeterminate length of the slatwall extrusion and the indeterminate width of its panels.
